UNITED STATES PATENT OFFICE

150,263

DESIGN FOR A HELICOPTER

Igor I. Sikorsky, Long Hill, Conn., assignor to
United Aircraft Corporation, East Hartford,
Conn., a corporation of Delaware

Application March 20, 1946, Serial No. 127,693

Term of patent 7 years

(Cl. D71—1)

To all whom it may concern:

Be it known that I, Igor I. Sikorsky, a citizen of the United States, residing at 5814 Main Street, Long Hill, Bridgeport, in the county of Fairfield and State of Connecticut, have invented a new, original, and ornamental Design for a Helicopter, of which the following is a specification, reference being had to the accompanying drawing, forming a part thereof.

Fig. 1 is a top plan view of a helicopter with two of the rotor blades broken away;

Fig. 2 is a side elevational view, with the forward rotor blade broken away;

Fig. 3 is a front elevational view; and

Fig. 4 is a top perspective view with one rotor blade removed and the other two blades broken away.

The characteristic features of my design re-

side in the portions shown by means of full lines in the drawing.

I claim:

The ornamental design for a helicopter, as shown and described.

IGOR I. SIKORSKY.
